UNITED STATES PATENT OFFICE.

THOMAS W. SMITH, OF DELPHOS, OHIO.

STEEL FENCE-POST.

1,117,459.

Specification of Letters Patent. Patented Nov. 17, 1914.

Application filed September 25, 1913. Serial No. 791,827.

To all whom it may concern:

Be it known that I, THOMAS W. SMITH, a citizen of the United States, residing at Delphos, in the county of Allen and State 5 of Ohio, have invented certain new and useful Improvements in Steel Fence-Posts, of which the following is a specification, reference being had therein to the accompanying drawing.

10 This invention relates to a fence post and has for its object the production of a metallic post which is so formed as to allow a wire or mesh fence to be easily placed and held in firm engagement therewith.

15 Another object of this invention is the production of a metallic fence post having its front face formed to constitute a binding action upon the wire or mesh whereby the key will be held in firm engagement 20 within the rib of the post.

With these and other objects in view, this invention consists in general of certain constructions and arrangements of parts as will be clearly brought out in the following 25 specification and claim.

30 In the accompanying drawings, Figure 1 is a perspective view of the complete fence. Fig. 2 is a transverse sectional view taken through the post. Fig. 3 is a central longitudinal section taken through one of the posts. Fig. 4 is an elevation of the key.

35 Referring to the accompanying drawings by numerals, 1 indicates the two converging sides of the post which are connected by the front 2. This front 2 is provided with a centrally-arranged, longitudinally-extending rib 3 which extends outwardly and is provided with a number of notches 4. The portion of this front 2 upon each side of the 40 rib 3 is bowed so as to extend inwardly as indicated in dotted lines in Fig. 2 before the wire or mesh is placed in engagement with the post.

45 The wire as shown in the accompanying drawing comprises vertical strips 5 and longitudinal strands 6 having notched portions 7 whereby the strips and strands may be placed in engagement with each other and held in position by means of the tie wires 8. 50 When this wire is placed in engagement with the post, the longitudinal strands 6 will rest within the notches 4 and will be held in position by means of the key 9. This key 9 comprises an elongated body 55 having a bent finger 10 at its upper end

which fits over the upper end of the rib 3 for preventing the key 9 from passing downwardly and out from engagement with the rib 3. After this key 9 has been placed in the rib 3, it will bear upon the forward inner portion of the rib 3 and upon the strands 6 which are positioned within the notches 4. This action will cause the strands 6 to bear firmly upon the front 2 adjacent the forward portions of the sides 1. By drawing upon this front 2, the front will assume the position illustrated in full lines in Fig. 2 and as the strands 6 are firmly bound in engagement with the front 2, the key 9 will also be firmly held within the rib 3 and will thereby be prevented from accidentally moving out from the interior of the rib 3.

50 By carefully referring to the drawings it will be seen that when the fence is in an assembled position, the strands will each bear upon three portions of the post and key whereby the same will be prevented from slipping and will be held in its correct position. The key 9 will bear upon the strands 6 when the same are placed within the notches 4, while the front 2 will bear at two different points upon each strand and will be firmly bound in engagement with the strands 6 by reason of the fact that the key 9 will draw slightly outward upon the rib and will cause the front 2 to move from its normal position indicated in dotted lines in Fig. 2 whereby the several parts of the fence will be firmly held in assembled position.

55 From the foregoing description, it will be seen that a simple fence post has been produced which is so formed as to give slightly for constituting a binding engagement with the wire fence or mesh whereby the wire will be held in firm engagement with the post.

95 What is claimed as new is:—

100 A fence post of the class described comprising a plurality of converging sides, a front portion integrally connecting said converging sides, said front portion being of resilient construction and provided with a centrally-arranged vertically-extending rib, said rib being provided with notches adapted to receive the strands of a wire fence, said front portion extending at acute angles to said converging sides and extending slightly inwardly adjacent said rib, a key inserted 105 within said rib, said key adapted to bear 110

upon the strands of a fence after the same have been placed in said notches whereby said resilient front portion will be drawn slightly outward adjacent said rib for binding the wire strands in engagement with said front portion adjacent each of said converging sides whereby said key will be held in position within said rib and the

wire strands will be held in a taut position and prevented from slipping past said post. 10

In testimony whereof I hereunto affix my signature in presence of two witnesses.

THOMAS W. SMITH.
